[57] CLAIM

The ornamental design for a beer keg, as shown and described.

DESCRIPTION

FIG. 1 is a perspective view showing our new design; FIG. 2 is a side elevational view thereof, the opposite side is the same;

FIG. 3 is a front elevational view thereof, the rear elevational view is the same;

FIG. 4 is a top plan view thereof;

FIG. 5 is a bottom plan view thereof;

FIG. 6 is a top plan view of a second embodiment of the beer keg similar to that shown in FIG. 4;

FIG. 7 is a top plan view of a third embodiment of the beer keg similar to that shown in FIG. 4;

FIG. 8 is a top plan view of a fourth embodiment of the beer keg similar to that shown in FIG. 4;

FIG. 9 is a top plan view of a fifth embodiment of the beer keg similar to that shown in FIG. 4;

FIG. 10 is a top plan view of a sixth embodiment of the beer keg similar to that shown in FIG. 4;

FIG. 11 is a top plan view of a seventh embodiment of the beer keg similar to that shown in FIG. 4.

FIG. 12 is a top plan view of an eight embodiment of the beer keg similar to that shown in FIG. 4;

FIG. 13 is a top plan view of a ninth embodiment of the beer keg similar to that shown in FIG. 4;

FIG. 14 is a top plan view of a tenth embodiment of the beer keg similar to that shown in FIG. 4;

FIG. 15 is a perspective view of the embodiment of FIG. 6;

FIG. 16 is a section view taken along lines 16—16 in FIG. 15;

FIG. 17 is a perspective view of the embodiment of FIG. 7;

FIG. 18 is a section view taken along lines 18—18 in FIG. 17;

FIG. 19 is a perspective view of the embodiment of FIG. 8;

FIG. 20 is a section view taken along lines 20—20 in FIG. 19;

FIG. 21 is a perspective view of the embodiment of FIG. 9;

FIG. 22 is a section view taken along lines 22—22 in FIG. 21;

FIG. 23 is a perspective view of the embodiment of FIG. 10;

FIG. 24 is a section view taken along lines 24—24 in FIG. 23;
FIG. 25 is a perspective view of the embodiment of FIG. 11;
FIG. 26 is a section view taken along lines 26—26 in FIG. 25;
FIG. 27 is a perspective view of the embodiment of FIG. 12;
FIG. 28 is a section view taken along lines 28—28 in FIG. 27;

FIG. 29 is a perspective view of the embodiment of FIG. 13;
FIG. 30 is a section view taken along lines 30—30 in FIG. 29;
FIG. 31 is a perspective view of the embodiment of FIG. 14; and,
FIG. 32 is a section view taken along lines 32—32 in FIG. 31.
The sides and bottom of the beer keg are the same in all embodiments.
